LUMINAIRE HOUSING

Carle E. Rackley, Westlake, Ohio, assignor to Westinghouse Electric Corporation, East Pittsburgh, Pa., a corporation of Pennsylvania

Filed Jan. 27, 1960, Ser. No. 59,187

Term of patent 14 years

(Cl. D48—23)

Fig. 1 is a top and side perspective view of the luminaire housing, showing my new design;

Fig. 2 is a top plan view thereof;

Fig. 3 is a side elevational view thereof;

Fig. 4 is an end elevational view thereof; and

Fig. 5 is a partial sectional elevational view as seen along line V—V in Fig. 2, it being understood that the luminaire housing is symmetrical.

The characteristic features of the design for a luminaire housing consisting of spaced substantially rectangular raised ribs on two sides of the top of the luminaire hous-

ing, the spaced ribs being downwardly tapering towards their outer extremities and generally defining variedly sized areas therebetween as shown.

I claim:

The ornamental design for a luminaire housing, substantially as shown and described.
